ELECTRIC RAZOR

Taisuke Ono and Shima Ito, Osaka, Japan, assignors to
Matsushita Electric Works, Ltd., Osaka, Japan

Filed Feb. 24, 1971, Ser. No. 118,583

Term of patent 14 years

Int. Cl. D28—03

U.S. Cl. D95—3

FIG. 1 is a side elevational view of an electric razor, showing my new design with the cover in place, the appearance being the same from all sides;

FIG. 2 is an exploded front elevational view of the razor with the cover removed, the rear being substantially a mirror image thereof;

FIG. 3 is a fragmentary side elevational view with the cover removed and omitted for convenience in illustration, the opposite side being substantially a mirror image thereof;

FIG. 4 is a top plan view with the cover in place, as seen from the top of FIG. 1; and

FIG. 5 is a top plan view with the cover removed and omitted as seen from the top of FIG. 3.

We claim:

The ornamental design for an electric razor, as shown and described
